UNITED STATES PATENT OFFICE.

THOMAS WILSON WRIGHT, OF LEITH, SCOTLAND.

ALBUM FOR HOLDING DISK RECORDS.

958,059.

Specification of Letters Patent. Patented May 17, 1910.

Application filed June 12, 1908. Serial No. 438,158.

To all whom it may concern:

Be it known that I, THOMAS WILSON WRIGHT, a subject of the King of England, and resident of Leith, Scotland, have invented Improvements in Albums for Holding Disk Records, of which the following is a specification.

This invention relates to improvements in the envelop leaves of albums for holding the disk records of talking machines.

In the accompanying drawing, Figure 1 shows an album for holding disk records of talking machines, constructed with my improved envelop leaves. Fig. 2 is an enlarged view of one of the leaves only, showing only one side thereof. Fig. 3 is a sectional view of the leaf as shown in Fig. 2, but somewhat enlarged with regard to its thickness. (For the sake of better illustration.)

Now, referring to the drawing, A represents the envelop leaf, which may be somewhat similar in shape to the ordinary envelop leaf at present in use; but in accordance with my improvements, the opening *a* of the envelop to receive the disk, is toward the inside or hinge B, Fig. 1, of the album instead of at the outside edge of the album as hitherto, in which latter case a clasp is usually necessary to prevent the disk falling out; whereas by inserting the disk at the hinge side of the envelop or leaf, the disks are retained in the album without such clasp.

I prefer that each leaf of the album be composed of two envelops A, as shown more particularly in Fig. 3, glued back to back, and also that each leaf be provided with the flaps *a'*,—one at each side. Also that the envelop or pocket portions A have the open-

ings *a'* so that a person may ascertain what 40 the particular title of the record is before removing it from the envelop.

The corners of the envelops may be cloth bound to strengthen and prevent them readily cutting.

The flaps *a'* permit of the records being more readily removed than would be the case if the end of the envelop were carried right on, close up to the hinge. Further, the said flaps somewhat act as filling pieces 50 to allow for the thickness of the disks and so that the album when filled with the disks, lies flat.

Having fully described my invention, what I claim and desire to secure by Letters 55 Patent is:—

1. In an album, a plurality of leaves, each leaf comprising two envelops fastened back to back, the faces of said envelops having apertures therein, and slits near the bound edges of said leaves, and flaps on said envelops adapted to lie flush with the outer surface of said leaves and ending in proximity to said slits.

2. In an album, a plurality of leaves, each leaf comprising two envelops fastened back to back, said envelops adapted to contain disk records and having slits near the bound edges thereof, the slits in the two envelops comprising one leaf being approximately 65 70 opposite one another.

In testimony whereof I have hereunto set my hand in the presence of two subscribing witnesses.

THOMAS WILSON WRIGHT.
